UNITED STATES PATENT OFFICE.

BIRAM C. DAVIS, OF BINGHAMTON, NEW YORK.

HAND-MACHINE FOR WIRING BLIND-RODS.

Specification of Letters Patent No. 25,726, dated October 11, 1859.

To all whom it may concern:

Be it known that I, BIRAM C. DAVIS, of Binghamton, in the county of Broome and State of New York, have invented a new and useful Improvement on Machines for Wiring Blinds; and I do hereby declare that the following is a full, clear, and exact description of the construction and operation of the same, reference being had to the annexed drawings, making a part of this specification, in which—

“Figure 1” is a perspective view of a hand machine for wiring blinds; “Fig. 2,” is a view showing the manner in which the blind rod is connected to the slats; and “Fig. 3,” is a view showing the adjustable arrangement for securing the window blinds while operating in connecting the rods to the slats.

The operation of this machine is as follows: The blind is secured to the frame (K) by turning the crank (N,) which adjusts the frame by means of a right- and left-hand screw, which leaves the stationary bar (B,) in the center and thus connecting the rod (C,) in the center of blinds of any width. The machine “Fig. 1” is then taken and the needle “J” passed through a trough containing the staples which thus picks them up in sufficient quantities. The form “A” or machine is then placed over the rod “C” and straddles the slat “D,” the lower claws of the form “A” being secured under the blind by the stationary bar “B,” which thus brings the edge of the slat “D” and the eye of the staple in rod “C” into the proper position. The joint lever “G” is then brought down and the slide “I” opens the way for the staples to pass in and is so constructed as to permit only one staple to pass in at a time; which said staple is then

passed through the eye of the staple in the rod “C” into the slat (D) connecting the rod to the slats as shown in “Fig. 2” which is placed from one slat to the other throughout the whole length of the blind.

In setting the staples in the rods they are placed in the bed (“O”—the machine is then placed straddle of the rod “C” and is secured by the lower claws to the gage 50 “F”—said machine is moved from one notch or catch to the other throughout the whole length of the rod. The screw “M” is for the purpose of varying the staples to their proper depth. The spring (L) keeps 55 the lever in a raised position.

Having thus described my invention as an improvement on other machines of the same class, what I claim as new and improved is.

1. The setting form “A” which sets over the rod “C” and straddles the slats “D” and which is secured under the blind by means of the stationary bar “B” in such a manner as to set the staples through the eye 65 of the staples in the rod (C) into the slats “D,” “D,” being the equivalent means employed for setting the staples into the rod “C” in combination with the adjustable arrangements “K” operating substantially as described.

2. I claim, in combination with the form “A,” the joint lever “G,” flange rod or driver (H), dividing slide “I,” inclined needle bar “J,”—the whole being arranged 75 substantially as described and for the purpose set forth.

Dated September 27th 1859.

BIRAM C. DAVIS.
